CORNICE CURTAIN POLE

Filed Oct. 9, 1930

Inventor
Charles W. Kirsch
Rudolph J. von Lotz
Attorney.

UNITED STATES PATENT OFFICE

CHARLES W. KIRSCH, OF STURGIS, MICHIGAN

CORNICE-CURTAIN POLE

Application filed October 9, 1930. Serial No. 487,418.

This invention relates to improvements in so-called "cornice" curtain poles and has for its main object to provide a device of this character which comprises a pair of brackets 5 and an intervening pole or cornice element which is supplied in long lengths to dealers and cut to desired lengths by the latter and wherein the brackets are permanently fitted at the factory with end or corner cornice elements of design and contour corresponding with that of the intervening piece aforesaid without requiring accurate workmanship on the part of the dealer in so cutting said intervening piece as to accurately abut at its ends 10 against faces of end or corner elements carried by the brackets and wherein the extremities of the said intervening piece are so hidden as not to disclose poor workmanship on the part of the dealer.

20 The invention is fully illustrated in the accompanying drawings, wherein:

Fig. 1 is a top plan view of a cornice curtain rod constructed in accordance with the invention.

25 Fig. 2 is a vertical section of the same on the line 2—2 of Fig. 1.

Fig. 3 is a vertical section of the same on the line 3—3 of Fig. 2.

30 Fig. 4 is a fragmentary plan section of the same on the line 4—4 of Fig. 3.

Fig. 5 is a perspective view of one of the brackets of the structure.

35 Fig. 6 is a perspective sectional view showing an end portion of the cornice element disposed between and supported by the brackets.

Fig. 7 is a fragmentary detail perspective view of a corner portion of a cornice curtain pole of different type than that shown in Figs. 1 to 5, inclusive.

40 Cornice curtain poles are made up of supporting brackets and picture frame mouldings. The latter usually present plane or flat rear faces while the front faces and, in many instances, the top and bottom edges thereof are of fanciful contour.

Heretofore, as far as I am informed, it has been the customary practice to construct cornice curtain poles by mitre-joint joinder of a middle or body member with two end or arm pieces or by providing corner ornaments 50 presenting flat faces opposed to the ends of the middle or body member and the outer ends of the end or arm members of the structure, said corner pieces being of a design and contour different from that of the body and 55 end members. An exemplary illustration of a structure of the last-mentioned type is disclosed in and by United States Letters Patent No. 1,563,619, dated December 1, 1925, wherein the said corner elements are attached 60 to the middle and end members by means of dowel-pins. Other exemplary structures of this general type are disclosed by Letters Patent Nos. 1,652,365 and 1,579,134.

65 In these structures very accurate workmanship is obviously required to assemble properly the component elements of the structure in order that no free spaces or cracks are disclosed at the joints and, furthermore, the corner pieces are of a design differing very materially from the companion elements.

70 Uniformity of design and contour of the component elements of the cornice curtain pole are very desirable for artistic reasons 75 while the elimination of the necessity for accurate workmanship in effecting assemblies is obviously very desirable from the standpoint of practicability.

80 Hence, the present invention has for its general object to provide a structure which combines practicability of construction and assembly with the retention or provision of artistry of the highest order with respect to such structures.

85 As shown in the accompanying drawings, each of the brackets 1, usually of wood, is provided at its outer end with a short section 2 of the picture frame moulding corresponding in contour and design on its exposed faces 90

with the main or middle member 3. In Figs. 1 to 5, inclusive, the section 2 is associated with a short end piece 4 of the same contour and design as the main or middle member 3 so disposed as to become accurately aligned with the latter when it is inserted between a pair of said brackets 1, whereas in Fig. 7, the sections 2^a and 4^a are mitre-jointed to form a corner element, the section 2^a being also suitably secured to the outer side face of the bracket 1. In both types the sections 4 and 4^a, respectively, project appreciably beyond the inner side face of the bracket 1 and have their rear face portions of the projecting parts cut away as indicated at 5 in such a manner and to the degree necessary to permit the end portions of the middle piece 3 to be inserted behind the said projecting portions of the sections 4 and 4^a, respectively, and in the case of the structure of Figs. 1 to 5 inclusive, become aligned with the section 4. In this last-named structure the section 2 also projects beyond the outer side face of the bracket 1 and the rear face of this projecting portion is cut away to correspond to and closely fit the contour of the front face of the section 4.

The accurate work required to produce the sections 4 and 2 with the side faces of the former and the free end of the latter conforming in contour and finish with the front faces thereof and cutting away the rear face portions of the section 4 as above described, is comparatively easily and cheaply done at the factory whereas in the workshop of the dealer, it would be a very difficult and expensive undertaking. Hence, economy dictates that as much as possible of the finished product shall be produced at the factory and salability dictates that the dealer or user shall be enabled to effect the balance of the assembly without the exercise of appreciable skill or labor.

In order to reduce the latter to the minimum and at the same time preserve the strength of the finished structure, each bracket is provided in its inner side face with a vertical recess 6 which extends from its upper edge to a point between its upper and lower edges. This recess is bridged adjacent its lower end by sheet-metal plate 7 having upwardly projecting arms 8, the outer edges of which abut against the side walls of said recess 6, said plate 7 being disposed in the transverse recess 9 which is of a depth substantially equal to the thickness of the plate 7. The recess 6 is spaced from the front edge of the bracket 1 a distance equal to the thickness of the member 3 with due allowance for projecting portions of its front face, said recess being parallel with the said front edge of the bracket 1.

The spacing of the plate 7 from the upper edge of the bracket 1 is determined by the width of the angle plate 10 which is mounted

on the inner or rear face of the member 3 with its upper edge flush with the upper edge of the latter as is clearly shown in Fig. 6. The body portion of this plate is provided with a plurality of longitudinal slots 11 through which the fastening screws 12 extend, thereby rendering said plate 10 adjustable longitudinally of the member 3. The flange 13 of the latter is intended and adapted to abut against the inner wall of said recess 6 while the recess 14 in the lower edge of the plate 10 is adapted to receive an arm 8 of the plate 7 and is so spaced from the flange 13 as to receive said arm 8 when the flange 13 abuts against said inner wall of said recess 6, said recess 14 will receive said arm 8.

From the foregoing it will be obvious that the dealer or user of the cornice curtain pole of this invention may cut the member 3 from a long piece without special regard to accuracy as to the saw-cut being exactly perpendicular to the longitudinal axis of said member 3 and may cut said piece 3 slightly shorter than required. The plates 10 are then easily secured to the member 3 in accurately correct position because the upper edges of the members 3 and 10 constitute a sufficient guide for this purpose while the slots 11 permit of ample adjustment to overcome any inaccuracy in the positioning of the plates 10 longitudinally of the members 3.

The above described fixtures 7 and 10 or equivalents thereof are desirable to cause the member 3 to constitute a structural member which serves to hold the brackets 1 against lateral movement or swing under the influence of unusual stress such as children pulling on the draperies suspended from the structure.

After the brackets 1 are mounted, the space between their opposed faces is measured and the proper length of the member 1 cut from a long length piece and is then fitted with the angle plates 10, the screws 12 being left sufficiently loose to permit said plates 10 to be properly adjusted thereon by dropping the member 3 behind the section 4 or 4^a, the plates 10 being then adjusted digitally until the recesses 14 receive the arms 8 of plate 7. At least one of the screws 12 of each plate is then tightened.

I claim as my invention:

A cornice curtain pole comprising a pair of supporting brackets and a plurality of pieces of a picture moulding, said pieces including a middle or body section, two end sections and two short sections, said end sections being permanently mounted on said brackets and said short sections being permanently mounted on the outer faces adjacent the opposed ends of said end sections and projecting in part beyond the opposed ends of the latter, the inner faces of the said

projecting portions of said short sections being shaped to accommodate the outer face portions of the middle section and permit the latter to be inserted with its end portions disposed behind the same and in alignment with said end sections, and means for detachably engaging said middle section with said brackets for support thereby and maintaining the same in said alignment with 10 said end sections, said means also adapted to co-operate with said middle portion to maintain said brackets in predetermined spaced relation to each other.

In testimony whereof, I have hereunto set 15 my hand.

CHARLES W. KIRSCH.
